UNITED STATES PATENT OFFICE

116,541

DESIGN FOR A SELECTIVE COUNTER BOX FOR AUTOMATIC PHONOGRAPHS

Roy Nielander, San Antonio, Tex.

Application January 23, 1939, Serial No. 82,537

Term of patent 14 years

To all whom it may concern:

Be it known that I, Roy Nielander, a citizen of the United States of America, residing at San Antonio, in the county of Bexar and State of Texas, have invented a new, original, and ornamental Design for a Selective Counter Box for Automatic Phonographs, of which the following is a specification, reference being had to the

accompanying drawing, forming a part thereof.

The figure is an isometric view of a selective counter box for automatic phonographs, showing my new design.

I claim:

The ornamental design for a selective counter box for automatic phonographs, as shown.

ROY NIELANDER.
